COMPASS

Carl G. Larson, Attleboro, Mass., assignor to
Larson Tool and Stamping Company, a cor-
poration of Massachusetts

Application May 19, 1932. Serial No. 612,179

7 Claims. (Cl. 33—157)

This invention relates to a compass and has for one of its objects to provide a construction which will prevent play about its pivotal connecting parts and be rigid against usual operating strains that more accuracy may be obtained in its use.

Another object of the invention is the provision of a construction which may be assembled with greater speed and accuracy that the cost 10 of producing the same may be reduced.

Another object of the invention is the provision of an assembly, the parts of which cannot become accidentally detached and lost.

A further object of the invention is the provision of a resilient spring which will give greater flexibility of action of the parts and yet one which may be used for positioning the parts to hold them in desired relation when assembled.

With these and other objects in view, the invention consists of certain novel features of construction, as will be more fully described, and particularly pointed out in the appended claims.

In the accompanying drawing:

Fig. 1 is a side elevation of my compass.

Fig. 2 is a view similar to Fig. 1 showing the same in partially spread position with parts broken away showing the branches of the compass partly in section.

Fig. 3 is a perspective view of the yoke member of the compass.

Fig. 4 is a perspective view of the assembly of the yoke, threaded adjustment member and nut.

Fig. 5 is a side elevation of a fragmental portion of the compass with the lower part of the branches broken away.

Fig. 6 is a section on line 6—6 of Fig. 1.

Fig. 7 is a section on line 7—7 of Fig. 6.

Fig. 8 is a perspective view of one of the branches or legs of the compass.

Fig. 9 is a perspective view showing a modified adjustment member in the permanently assembled suit.

In the formation of compasses, it is desirable that the compass should maintain a certain 45 rigidity about its pivotally connected parts so that accuracy may be had in movements which it is adapted to perform. Also, it is desired that the compass be so formed that the parts will not become easily separated and lost or mislaid, and 50 in order to accomplish these results, I have provided a special unit assembly which is mounted upon the pivot pin connecting the branch arms of the device and when so mounted cannot be detached therefrom to become lost, and by an 55 improved provision of yoke I cause the arms to

have a rigid mounting, and I also provide a spring which is so arranged as to give greater flexibility and to also assist in maintaining the parts in their desired relation; and the following is a detailed description of the present embodiment of this invention illustrating the preferred means by which these advantageous results may be accomplished.

With reference to the drawing, 10 designates one of the branches or legs of the compass provided with a spur point 11, and 12 the other branch or leg of the compass provided with a pencil 13 held in by the resiliency of the hollow leg or a spur point such as 12 may be provided if desired. These branches are both formed of 65 hollow sheet stock and are each provided with laterally extending portions 14 and 15 which are each pressed inwardly as at 18 and 19 from the opposite sides thereof to form circular cups or recesses which nest one within the other and 70 through openings 16 in the bottom of these depressions there extends a pivot pin 17. The telescoping of the parts 14 and 15 and the nesting of the depressions assist in bracing and stiffening the branches or legs in their pivotal 75 movement about the pin 17. In each of the branches there is a notch 20 having generally parallel side edges 21 and a bottom edge 22 at right angles thereto.

A spring 23 is coiled a plurality of times about 80 the pivot pin 17 in order to give easier action and greater flexibility with its end portions 24 and 25 extending into each of the hollow or tubular branches urging them to swing apart about the pivot 17. Although any number of 85 coils may be used I have here illustrated three coils 26 on the upper side of the pivot pin 17.

In order to control or govern the movement of the branches of the compasses I have provided a unit assembly as shown in Fig. 4, the same consists of an adjusting screw 27 with an integral head 28, a nut 29 threadingly engaging the threads of the member 27 and a yoke 30 through which the nut applies pressure to the branches of the compass.

The yoke member is formed from sheet stock and is folded as at 37 providing a generally cylindrical portion 38 to receive the shank 27 of the adjustable member with the parts 39 of this yoke lying more or less closely together as shown 100 in Fig. 4, while the free ends 40 are each spread or branched outwardly as illustrated in Figs. 3 and 4, and then bent inwardly to form lips 41 so as to provide a generally rectangular form 105 with the inherent spring of the stock forcing the 110

same outwardly to engage the parallel edges 21 of the notch 20 and with the lips 41 resting against the bottom edge 22 of this notch at spaced points. Thus I provide a two-point bearing or point of rest of the yoke on each of the branches of relatively wide bearing surfaces which rigidly support the same. The increase of the bearing surfaces of the free ends of 40 on the bottom edges of the notches 20 steadies the lower portions of the yoke 30 and adds greatly to the rigidity of the joint. As pressure is applied by means of the nut 29 the yoke will be forced downwardly to force the branches about the pivot 17 against the tension of the spring 23 to obtain the desired adjustment of the parts.

This unit shown in Fig. 4 is assembled by first placing the nut in position on the threaded shank of the member 27 and then positioning the yoke thereon as illustrated in Fig. 4 after which the end of the member 27 is flattened as at 31, thus spreading the same and preventing removal of the parts so assembled, after which an opening 32 is pierced in this flat portion to receive the pivot pin 17 pivotally joining the branches of the compass together.

In the illustration which I have shown, in order that the parts may be centralized, the flattened portion 31 is offset with reference to the center of the shank 27 as illustrated in Fig. 6 so that the coils or bends 26 of the spring are received two on one side and one on the other side of this member in its position on the pivot 17. By this arrangement the member is held in desired centralized position by means of the bends of the spring between the two depressions 18 and 19 of the compasses.

In Fig. 9 I have illustrated a modified form of the lower end of the screw in which the parts are separated to form a spaced bearing portion and one to centralize itself with reference to the arms by reason of its being offset on both sides of its center and will thus receive one of the bends of the spring between these bifurcated portions and one on each side to assist in steadyng and providing a balanced construction.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. An instrument comprising two branches, a pivot pin for connecting said branches together, means for adjusting and maintaining said branches in desired position including a yoke having spaced apart, flat lip portions in engagement with each of said branches at two spaced points thereof to steady the same.

2. An instrument comprising two branches, a pivot pin for connecting said branches together, a threaded member extending outwardly from said pivot, and a yoke embracing said threaded member and having spaced apart, flat lip portions providing spaced points of engagement with each of said arms. 80

3. An instrument comprising two branches, a pivot pin for connecting said branches together, means for adjusting and maintaining said branches in desired position including a yoke having engagement with each of said branches at two spaced points to steady the same, said yoke being formed of sheet stock and being partly folded upon itself with the folded portions in contact, and said portions being branched outwardly and spaced apart at their free edges. 85 90

4. An instrument comprising two branches, a pivot pin for connecting said branches together, means for adjusting and maintaining said branches in desired position including a yoke having engagement with each of said branches at two spaced points to steady the same, said yoke being formed of sheet stock and being partly folded upon itself with the folded portions in contact, and said portions being branched outwardly and spaced apart at their free edges. 95 100

5. An instrument comprising two branches, a pivot pin for connecting said branches together, said branches each having a square sided notch in the upper end and means for adjusting said branches about the pivot including a yoke having spaced apart flat lip portions engaging the opposite side edges of each notch at points spaced apart. 105 110

6. An instrument comprising two branches, a pivot pin for connecting said branches together, said branches each having a square sided notch in the upper end and means for adjusting said branches about the pivot including a yoke having resiliently spaced apart flat lip portions engaging the opposite side edges of each notch with resilient pressure at points spaced apart. 115 120

7. An instrument comprising two hollow branches, a pivot pin connecting said branches together and a spring having a plurality of coils about said pin with an end portion extending into each of said branches, an adjusting screw 125 having an end portion offset from the longitudinal center of said pin and engaging said pin, said offset portion dividing said pin into two unequal parts, one part receiving more of said coils than the other by reason of said offset 120 whereby said parts may be maintained in generally balanced relation.
